N. H. Brown.

Suspension Bridge.

№ 12,155.

Patented Jan. 2, 1855.

UNITED STATES PATENT OFFICE.

WILLIAM H. BROWN, OF ERIE, PENNSYLVANIA.

SUSPENDED PURCHASE.

Specification of Letters Patent No. 12,155, dated January 2, 1855.

To all whom it may concern:

Be it known that I, WILLIAM HOGG BROWN, of Erie, in the county of Erie and State of Pennsylvania, have invented a new and useful Improvement in Suspended Purchases for Transporting, Raising, Lowering, and Placing Heavy Burdens; and I do hereby declare that the following is a full description thereof.

10 My improvements are to be chiefly employed in the erection of bridges over streams or ravines. They consist in providing a suitable cable stretched across between the banks of the river which cable forms a fixed track over which a suitable carriage or truck traverses, the weight to be lifted and transported being suspended below the truck by means of a series of tackles.

Figure 1, in the accompanying drawings 20 represents in perspective the general uses and application of my improvement in bridge building. Fig. 2, is an enlarged side elevation of my improved truck, and improved fixed and movable clutch blocks, as 25 applied ready for operation. Fig. 3, is a front view of my improved blocks previous to, and after clutching. Fig. 4, is a view of the same clutched together. Fig. 5, is a view of the same in the act of being 30 detached or uncoupled. Fig. 6, is a side elevation of my equalizing beams. Fig. 7, is a perspective view showing the method of combining the strength of more than one suspension cable.

35 Similar letters of reference indicate the same parts.

A, A', suspension towers placed on the opposite banks of the river over which the bridge is to be built; B, B', B², B³, suspension cables passing from tower to tower; C, frame of cable truck; D, main wheel of same; E, E', guide wheels; F, fixed clutch block; G, movable clutch block; H, lips on fixed block; H' cross bar of same; I, clutch bars on the movable block; G, J, hinges of the clutch bars; K, connecting rods between cap piece and clutches; K', cap piece; L, guide pin; M, connecting spring between clutch bars; N, O, P, guide blocks; Q, R, S, equalizing beams; U, U', guide falls; V, guy chain; W, metallic groove on the side of towers A, A'; W', eye bolt, working in the groove; X, friction wheels; Y, stonebinder.

50 In the construction of bridges across rivers, when piers are to be erected in the stream, the usual method of transporting

the stones and other materials, is to employ floats or boats, and to raise the materials by the employment of suitable derricks. Stagings and scaffolds are also employed. The 60 various operations of raising, elevating, and depositing the stones and other materials, consume much time, and consequently involve great expense.

The object of my improvement is to facilitate the workmen in the erection of all such structures, by providing a safe, easy and rapid means of transporting and depositing the stones and all other materials, without the employment of derricks, or any 65 of the usual scaffold appendages.

In the first place I erect upon the banks of the river in which the piers are to be built, two towers A, A', composed of wood or any other suitable material. I then 75 throw a suspension cable B, proportionate in size to the weight of materials to be transported, from one tower to the other, the ends of the cable being fastened in the ground in any suitable manner. The cable 80 thus stretched forms a fixed track over which my improved truck passes and repasses in its various errands of transportation. The truck is composed of a frame C, in the central upper part of which, the main 85 wheel D, is secured. The wheel D, is grooved, and so are the wheels E, E', in order that they may properly fit the surface of the cable over which they pass. Suitable straps extend from the wheel D, to the fixed 90 tackle F, the entire weight of the load to be moved being intended to be carried pendent directly below the wheel D. As the burden always remains far below the center of gravity of the truck, there is never 95 any liability in the wheels of the latter to slip off the cable.

We will now suppose that it is desired to convey a heavy weight from some position near one of the towers, to a point in the middle of the stream where the workmen are engaged in building a pier. The truck is brought over the spot where the burden happens to be placed, and secured from rolling down the incline of the cable, by 100 means of the guide fall U, as seen in Fig. 2. The weight is attached at *x*, on the movable block G, and by means of the purchase fall T, the burden is elevated, being raised until the tackle blocks F, G, clutch.

105 The clutch bars I, are attached to the sides of the tackle block G, having hinges

J, J. The clutches are held in a closed position by means of a spring M, Fig. 3. They are also attached to a movable cap piece K', by means of the connecting rods K. The red lines in Fig. 3, indicate the position of the clutch bars I, in the act of passing the lips H. As the block G, rises, the upper ends of the clutch bars I, strike the lips H, and are opened until the slots in the 10 clutch bars arrive opposite the lips when the spring M, closes the clutch bars and they fasten on the lips H, as seen in Fig. 4. The purchase fall T, is now relieved of all strain, the weight being entirely sustained 15 by the clutch bars.

In order to move the weight thus elevated to the desired position above the pier, it is only necessary to slacken the guide fall U, when the truck, carrying with it the burden, will move of its own gravity down the incline of the cable in the direction of arrow 1. Arrived over the pier, the guide fall U, U', are fastened, which secures the truck. The clutch bars are now detached, 25 and the burden is lowered by slackening the purchase fall T.

The clutches are detached by simply pulling upon the purchase fall T, and raising the movable block G, as seen in Fig. 5, 30 which causes the pin L, to pass through the opening in the cross bar H', and brings the cap piece K', in contact with the cross piece H', whereby the connecting rods, K, K, are straightened, and pressed down 35 to a line even with the centers of their joints which causes them to remain in that position and hold open the clutch bars I, I, clear of the ears H, H, as seen in Figs. 3 and 5. The clutches are afterwards brought up to 40 their clutching position by moving up the cap piece K, by hand.

It is obvious that the movement of the truck is controlled by the guide falls U, U', to which the requisite force must be applied. 45 When desired, the weight may be raised or lowered at the same time that the truck is moving.

We will suppose the truck to be moving in the direction of arrow 2, and that the 50 purchase fall T, (shown in red lines Fig. 2,) is fastened to the tower A. It is manifest that while the truck proceeds, the weight is also lowered with a speed proportionate to the number of sheaves in the blocks F, G. This plan of lowering the weight during transit to its destination, will be found very convenient where the burden is to be taken from an elevated point and deposited at a distance lower down; see Fig. 60 1 where the purchase fall T, is fastened to tower A, and the stone Y, is advancing in the direction of arrow, and at the same time descending toward the right pier in the river the angle of descent being indicated by the dotted lines. In the same man-

ner a weight may be elevated during the progress of the truck by fastening one end of the purchase fall, and pulling the truck away from the point where the purchase fall is secured by means of the guide falls. 70 A considerable saving in time is effected by these modes of raising and lowering the burden while in transition.

The guy chain V, is attached between the tackle block F, and arm C, in order to assist in retaining the perpendicularity of the block F, with the wheel D, when power is applied to the purchase fall T. 75

When it is desired to transport unusually large burdens, more than one suspension cable may be employed, and their strength so combined, as equally to support one burden. For this purpose I employ the equalizing beams Q, R, S, shown in Fig. 6. 80

In Fig. 7, four cables are represented as 85 in use, having a truck to each cable. The tackle blocks attached to two of the trucks are fastened to the beam R, and the remaining two, to beam S. The ends of central beam Q, pass through links which rest in the 90 centers of beams R, S, as shown. The burden is attached at Y.

If, from any cause, the cables should not each bear up its due portion of the burden, the inequality will be at once apparent, for 95 the equalizing beams being balanced in their centers, will be thrown out of line. When the weight is equally sustained the equalizing beams will all be parallel.

Upon the side of the tower A, a metallic 100 groove W, is attached in which the eye bolt W', slides, the eye bolt having a chain attached above and below, the upper part of the chain passing over the pulley X, and the lower part passing down to a convenient position 105 near the ground, where it passes around a winch. By turning the winch the eye bolt can be raised or lowered as desired, and the guide tackles easily brought into convenient position. The eye bolt W', and 110 guide block P, shackle together as seen in Fig. 2.

After the piers of a bridge have been finished, my apparatus may be then employed in laying the superstructure and all other 115 parts of the bridge. For this purpose, it is admirably adapted, since the trusses and other portions may be deposited in their places with very great rapidity. A glance at the sketch Fig. 1, will show the great convenience and superiority of my improvement 120 over the common methods of moving the materials used in the construction of similar works.

The expense of my apparatus is small; all 125 the rigging and trucks are portable, and may be carried from one point to another at convenience. The saving in expense which the use of my improvement affords, over the old methods, is immense. The same 130

amount of work is performed with less machinery, by fewer workmen, and in shorter time.

Each pair of sheaves of the clutch blocks 5 it will be observed are of different diameters in order to equalize the friction of the purchase fall.

Having thus fully described the nature of my invention I would state that I do not 10 claim a suspended cable, for transporting weights of any kind across ravines or streams; nor do I claim transporting bodies of any kind by means of a movable cable or catenary which is to be raised or lowered to 15 deliver the burden or weight at any intermediate place between its points of suspension or fastening, as these have been essayed. But

What I do claim as new and desire to set 20 cure by Letters Patent is—

1. In combination with a permanently suspended cable, a carriage provided with suitable block and tackle, by which a suspended weight of any kind may be trans-

ported to any given point, and then lowered 25 or raised, or by which it may be lowered or raised, as it is transported, at pleasure, substantially as described.

2. I also claim in combination with a suspended cable, a truck or carriage composed 30 of a main wheel D, guide wheels E E', and a flexible frame C, so that the wheels may adjust themselves to the line of the catenary as described.

3. I also claim the automatically coupling 35 and uncoupling of the blocks F, G, substantially in the manner and for the purpose set forth.

4. I also claim the system of equalizing beams Q, R, S, when combined with two, 40 three, or more cables, for the purpose of evenly distributing the weight upon the several cables as set forth.
